Des. 240,030
Patented May 25, 1976

240,030

STATION FOR ELEVATED RAILWAY

Lawrence K. Edwards, 565 Arantradero Road,
Palo Alto, Calif. 94306

Filed Oct. 2, 1973, Ser. No. 402,842

Term of patent 14 years

Int. Cl. D25—99

U.S. Cl. D25—4

FIG. 1

FIG. 2

FIG. 3

FIG. 1 is a side elevation of a station showing my new design;

FIG. 2 is an end elevation of the station; and

FIG. 3 is a top plan view of the station.

I claim:

The ornamental design for a station for elevated railway, substantially as shown.
